COMBINED TORCHÈRE AND BRIDGE LAMP

Filed Aug. 8, 1929

UNITED STATES PATENT OFFICE

LEROY C. DOANE, OF MERIDEN, CONNECTICUT, ASSIGNOR TO THE MILLER COMPANY, OF MERIDEN, CONNECTICUT, A CORPORATION OF CONNECTICUT

COMBINED TORCHÈRE AND BRIDGE LAMP

Application filed August 8, 1929. Serial No. 384,356.

The present invention relates to combined torchères and bridge lamps and is more particularly directed toward a torchère and bridge lamp arranged so that the torchère 5 part of the device may be detachably carried.

An object of the present invention is to provide a lighting appliance in the form of a combined torchère and bridge lamp by means of which one can have either the low intensity 10 downwardly directed light of the bridge lamp or the high intensity upwardly directed light of a torchère adapted for indirect lighting.

The present invention also contemplates making the lighting appliance so that the 15 torchère part can be detached from the bridge lamp part when not in use, thereby making it easier to move the bridge lamp about and permitting access to the interior of the torchère for cleaning. When the torchère part of 20 the unit is removed, the present invention contemplates that the remaining bridge lamp shall be of pleasing appearance without apparent mechanical means for attaching the torchère unit.

25 The accompanying drawings show, for purposes of illustrating the present invention, one of the many possible embodiments in which it may take form, it being understood that the drawings are illustrative of 30 the invention rather than limiting the same.

In these drawings:

Figure 1 is a side elevational view with 35 parts in section showing a combined bridge lamp and torchère with the torchère unit in place; and

Figure 2 is a fragmentary detached elevational view showing the torchère unit removed from the bridge lamp standard.

The bridge lamp part of the device may 40 embody a conventional base 10, tubular standard 11, bridge lamp arm 12, lamp socket 13, and shade 14. These parts may be made up in any desired ornamental manner. As here shown, the base 10 is covered by an ornamental spinning or stamping 15 to which is 45 attached a convenience outlet indicated at 16.

As here shown, the upper end of the standard 11 is provided with an ornamental tip or 50 finial 17 adapted to detachably receive a husk

or socket cover 18. This husk may have a suitable ornamental configuration, but is preferably so designed that it telescopes and fits closely over the finial or knob 17. The husk 18 carries a nipple 10 on which is secured 55 in the usual manner a lamp socket 20. The upper end of the socket cover or husk 18 carries an upwardly outwardly flaring conical reflector support and bulb cover 21 of any suitable pleasing configuration. This reflector support 21 carries a reflector 22 outwardly 60 flanged as indicated at 23 and held in place by a ring 24.

A high wattage lamp bulb 25 is carried in 65 the lamp socket 20 and the reflector 22 is designed so as to concentrate the light rays into a strong upward light beam so as to direct them to the ceiling. The current supply cord for the lamp socket is indicated at 26. It is provided with a plug 27 cooperative with 70 the convenience outlet 16.

When the device is in use as a combined 75 bridge lamp and torchère, the parts are in the position indicated and one can then obtain the high intensity indirect lighting of 80 the ceiling and the low intensity lighting from the bridge lamp. In case it is desired to dispense with the torchère unit, it may easily be lifted off the finial 17 and the cord 26 wound around the husk as indicated in 85 Figure 2. This part of the device may then be stored until it is again desired.

This type of lighting appliance provides 90 the user with an ornamental bridge lamp, with no suggestion of a torchère, which may 95 be converted whenever desired to a torchère. It is of course possible to make up the combined unit without the detachable feature of the torchère, in which case the torchère will be permanently carried on the lamp standard 90 and the wiring carried up inside the standard, the current being controlled by a suitable switch in the torchère socket.

It is obvious that the invention may be 95 embodied in many forms and constructions within the scope of the claims, and I wish it to be understood that the particular form shown is but one of the many forms. Various modifications and changes being possible, 100

I do not otherwise limit myself in any way with respect thereto.

What is claimed is:

1. A lighting appliance comprising a base, a lamp standard, a bridge lamp arm at the upper end of the standard, a lamp socket and shade carried by the bridge lamp arm, and a high intensity torchère unit surmounting the standard, the unit comprising 5 a single upwardly opening lamp socket, a husk about the lamp socket, an upwardly opening reflector support carried by the husk and surrounding the lamp, and a reflector about the lamp bulb to reflect the light 10 upwardly, and a current supply cord secured to the socket and adapted to supply current through a circuit independent of the circuit for the bridge lamp arm socket, the torchère unit being detachably carried by the upper 15 part of the standard and being completely removable therefrom.

2. The combination with a bridge lamp having a base, a convenience outlet in the base, a standard, a bridge arm, and an ornamental finial, of a detachable torchère unit 20 having provisions whereby it may be telescoped over the finial to support it on the standard, and a current supply cord with plug cooperable with the convenience outlet.

3. A torchère unit for combined bridge lamps and torchères, comprising a husk centrally recessed at its lower end and carrying at its upper end a lamp socket, a lamp bulb 25 in the socket, a reflector support and reflector 30 about the lamp bulb, and a current supply cord for the lamp socket, passing through the husk and adapted to be wound about the husk when the lamp is not in use.

Signed at Meriden, in the county of New Haven, and State of Connecticut, this 5th day of August, 1929.
